[57] **CLAIM**

The ornamental design for a "window treatment accessory", as shown and described.

DESCRIPTION

FIG. 1 is a perspective view of the claimed window treatment accessory;

FIG. 2 is a top plan view thereof;

FIG. 3 is a bottom plan view thereof;

FIG. 4 is a front view thereof;

FIG. 5 is a rear view thereof; and,

FIG. 6 is a right side view thereof the left side view being a mirror image of the right side view.

The broken line showing of a finial, partial curtain rod on FIG. 1 and mounting holes on FIG. 5 is for illustrative purposes only and forms no part of the claimed design.
